OR D 11,680

No. 11,680

March 16, 1880

UNITED STATES PATENT OFFICE.

WILLIAM C. BEATTIE, OF TAUNTON, MASSACHUSETTS, ASSIGNOR TO REED & BARTON, OF SAME PLACE.

DESIGN FOR FORK AND SPOON HANDLES.

SPECIFICATION forming part of Design No. 11,680, dated March 16, 1880.

Application filed January 19, 1880. Term of patent 7 years.

To all whom it may concern:

Be it known that I, WM. C. BEATTIE, a citizen of the United States, residing at Taunton, in the county of Bristol and State of Massachusetts, have invented and produced a new and original Design for Handles for Forks and Spoons, of which the following is a specification, reference being had to the accompanying photographic illustrations, forming part 10 thereof.

Figure 1 is the front, and Fig. 2 the rear, side of a fork ornamented by my design.

My design consists in a handle formed with a gradual taper from its narrow shank to its 15 wide end, with a transverse groove near the middle of the handle, the shank portion below the groove being ornamented by flowers embossed or struck up, while the portion of the handle above the groove is made with its 20 broadest half perfectly plain and polished and its narrowest half ornamented with flowers and a fancy margin, the front side of the handle showing the flowers in an urn and a bird perched in the midst of the same, and 25 the rear side showing simply a standing growth of flowers.

In the photographic illustration, *d* is the transverse groove near the center, below which, and extending to the point *a*, is embossed the

form of the petals, stems, and leaves of flowers. From *b* to *c* the handle is perfectly plain and polished, while from *b* to *d* is shown a standing growth of flowers capped over at the top by a triple arched and crested border. On the front side of the spoon shown in Fig. 1 35 the flowers are in an urn, *e*, and in among the flowers is perched a bird, *d*. On the rear side of the handle the bird and urn do not appear.

Having thus described my invention, what I claim as new is—

1. The design for the rear of the handle, consisting of the gradually-tapered edge, the cross-groove *d* near the middle, the embossed flowers from *a* to *d*, and the standing growth of flowers from *d* to *b*, and the contrasting 45 plain surface from *b* to *c*, as shown and described.

2. The design for the front of the handle, consisting of the gradually-tapered edge, the cross-groove *d*, the embossed flowers from *a* to *d*, the urn *e*, containing a standing growth of flowers with a bird perched therein, substantially as shown and described.

WILLIAM CHALLEN BEATTIE.
